UNITED STATES PATENT OFFICE.

FRANCIS M. ELKINTON, OF MILWAUKEE, WISCONSIN.

CABINET TRAFFIC SYSTEM.

Application filed May 25, 1925. Serial No. 32,722.

This invention relates to improvements in traffic systems, and more particularly to a compact card filing traffic system and cabinet therefor.

5 After the enactment of the regulatory statutes applicable to interstate and intra-state commerce, a need grew for the creation of traffic departments and traffic services for shippers and receivers, and now industries 10 generally maintain a traffic department, or use traffic services conducted by independent institutions.

It is, therefore, the principal object of the present invention to provide a traffic system 15 adapted to the needs of industries which will quickly and conveniently supply any needed traffic information, and which can be readily augmented from time to time.

A further object of the invention is to provide 20 a traffic system which will provide the user with everything in the way of transportation cost that is necessary in the marketing of his manufactured products, or in the purchase of raw materials.

25 A further object of the invention is to provide a traffic system which can be supplied for any commodity and which uses as a basis of information the territories to which shipments are made, the nature of the commodity, location of competitors and the territories wherein they ship, and quantities shipped by competitors.

Further objects of the invention are to provide 35 a traffic system which eliminates the necessity of all other forms of service, supplies instantly any wanted freight or express rate or routing to or from any given point, gives all information for claim handling, freight bill auditing, and other traffic 40 requirements, and which may be started small and gradually extended to cover any and all cases.

It is a further object of the invention to provide 45 a cabinet traffic system which is very simple, and is well adapted for the purposes described.

With the above and other objects in view, the invention consists of the improved traffic system, and its parts and combinations 50 as set forth in the claim, and all equivalents thereof.

In the accompanying drawing in which the same reference characters indicate the same parts in both of the views:

Fig. 1 is a fragmentary plan view of the 55 improved cabinet and traffic system with the drawer extended; and

Fig. 2 is a side view thereof.

Referring now more particularly to the drawing, it will be seen that the numeral 5 60 indicates a card cabinet having an extensible drawer 6. The drawer is divided by a medial transverse partition 7 and a longitudinal partition 8, into a pair of large forward compartments 9 and 10. A transverse partition 11, rearwardly of the partition 7 and parallel thereto, and a pair of partitions 12 and 13, divide the mid portion of the drawer into intermediate compartments 14, 15 and 16. Rear partitions 17 and 18 form an enlarged rear compartment 19 and side compartments 20 and 21, the compartments 19 being formed with an inclined bottom 22 so that the headings of all cards held therein will be visible from the front of the cabinet. 70 75

In use, the improved traffic system can be made up for any and all businesses and commodities, and the compartment 9 catalogues cards containing information relative to the outgoing product and said information is specific to the particular commodity for which the system is designed, and classifies the formation under the headings of the various States into which the outgoing product is shipped. As shown in Fig. 1, 80 85

headings 23 bearing the names of the States into which the product is shipped, are arranged in alphabetical order in the compartment 9 and specific information cards 24 are grouped with respect to the States and 90 towns to which they apply. The cards 24 grouped for each State are preferably provided in different colors and white cards may be used to contain rates, routings and tariff authority on all outgoing products. 95 Grouped with the white cards for each State may also be blue cards giving the rates of competitors to the same markets, and there may also be other colored cards containing express rates to the same markets. 100

The other forward compartment 10 also catalogues cards giving information relative to the specific commodity and particularly gives information in regard to all incoming raw materials used in the production of the 105 specific commodity. Headings 25 are provided bearing the names of the raw materials used, and information cards 26 are

grouped thereunder containing the rates, routing and tariff authority on the incoming raw materials classified.

Information relative to specific commodities is also classified in the intermediate compartment 15. Said compartment is divided by suitable heading of title cards 27 and specific cards 28 classified thereunder bear information relating to the rules, regulations, classifications, etc., applicable to specific commodities carried on the rate cards contained in compartments 9 and 10.

The small compartments 14 and 16 at each end of the compartment 15 may be used to contain extra or blank cards which may be filled in or used from time to time, as necessary.

The large rear compartment 19 contains heading cards 29 which are general in nature and apply to all commodities, being the same in all traffic systems designed under the present plan. Information cards 30 are catalogued under the correct heading cards and contain information with respect to rules, regulations, laws, forms, etc., applying to all transportation.

The small side compartments 20 and 21 may be used for holding application cards

for incoming and outgoing rates, the idea being for the user to mail said cards to the builder of the system when desired, and the specified rate cards will be returned to the user to augment the system.

It will thus be seen that the improved traffic system will supply any and all traffic information and is very convenient to use. Also, it can be readily expanded when desired. Also, the cabinet system is very simple and novel, and is well adapted for the purposes set forth.

What I claim as my invention is:

In a card cabinet, a drawer, a medial transverse partition and a forward longitudinal partition therein defining only a pair of large forward compartments, a transverse partition rearwardly of the medial transverse partition and a pair of side partitions between said transverse partitions defining intermediate compartments, and rear partitions between the rear wall of the drawer and said rear transverse partitions defining rear compartments, all of said compartments holding related cards.

In testimony whereof, I affix my signature.

FRANCIS M. ELKINTON.
